Patented Nov. 23, 1926.

UNITED STATES PATENT OFFICE.

JOHN WHISLER, OF OTTUMWA, IOWA.

JOINTER TABLE AND OPERATING MEANS THEREFOR.

Application filed February 16, 1925. Serial No. 9,557.

An object of this invention is to provide improved means for adjusting the altitude of a table or tables of a jointer or similar wood-working machine.

5 A further object of this invention is to provide improved means for locking and holding a table or tables in any selected altitudinal adjustment.

10 A further object of this invention is to provide improved means for supporting a table or tables, in a wood-working machine, in respect of altitudinal adjustment.

15 My invention consists in the construction, arrangement and combination of elements hereinafter set forth, pointed out in the claims and illustrated by the accompanying drawing, in which—

20 Figure 1 is a plan and Figure 2 a side elevation of a jointer embodying my improvements. Figure 3 is a side elevation, partly in section, on an enlarged scale, of one table of the jointer showing my improvements applied thereto. Figure 4 is an end elevation of the same. Figure 5 is a detail section on 25 the indicated line 5—5 of Figure 3. Figure 6 is a vertical section through one of the hinges. Figure 7 is a perspective of one of the T-plates employed in the machine.

25 In the construction of the machine as shown the numerals 10, 11 designate angle bars connected in parallel relation by cross-bars 12, 13 and adapted to be mounted rigidly in any suitable location, such as on a bench, stand or support not shown. The angle bars 10, 11 are adapted to support two tables, placed end to end, and supported by hinges so that said tables may be raised and lowered relative to said bars. Four hinges are provided for each table and they 30 and the tables are constructed as about to be described. Each hinge is formed of two parts, an angle plate 14 (Figure 6) and a link 15. The angle plate 14 is formed with a slot 16 in its base adapted to receive a bolt 17 (Fig. 3) whereby it may be secured to an angle bar 10 or 11, and also is formed with a hole 18 in its upright portion. The link 15 is formed with two bolt holes 19, 20 oppositely countersunk and adapted to receive bolts 21, 22. The heads of the bolts 21 are countersunk on the inner faces of the links and said bolts serve to pivot said links to the upright portions of the angle plates 14, while the bolts 22 have their heads countersunk on the outer faces of the links and serve to pivot said links to angle bars 23, 24 forming the lower portions of and supporting tables 25, 26. The tables 25, 26 and their supporting angle bars 23, 24 are rigidly connected and are placed end to end and 60 spaced apart, their adjacent ends being beveled or curved and adapted to overlap a cutter 27 carried by a shaft 28 journaled in suitable bearings 29, 30 on the angle bars 10, 11, one end portion of said shaft carrying a pulley 31 or suitable device whereby the shaft may be rotated by a power connected therewith (not shown). The eight hinges, four for each table, support the tables on each side, near each end and in 65 parallel relation with the angle bars 10, 11 at all times. T-plates 32, 33 are provided with bolt holes in the end portions of their heads adapted to receive bolts 34 whereby they may be secured to and depend from 70 central portions of the respective tables 25, 26. The stems of the T-plates 32, 33 extend transversely of and partially across the respective tables 25, 26 and are formed with vertical slots or notches 35, one slot in each 75 stem. Bearing plates 36, 37, of angular form, are mounted on the central portions of the cross-bars 12, 13 respectively. Each bearing plate 36, 37 is formed with bolt holes 80 side by side in its base adapted to receive 85 bolts 38 to fix it to its cross-bar. The upright portion 39 of each bearing plate is rounded on its top and is formed with a threaded aperture having its axis parallel 90 with and below the median line common to the tables 25, 26. Feed screws 40, 41 are threaded in the apertures of the upright portions of the bearing plates 36, 37 and extend in opposite directions therefrom. Each feed screw 40, 41 is formed with a reduced inner end portion 42, merging into the body of the screw by a conical shoulder 43 and is adapted to extend through a slot 35 in the stem of a T-plate 32 or 33 loosely. A washer 44 is mounted on each feed screw and is 95 formed with a conical hole adapted to receive and form a bearing for the conical shoulder 43 on the screw, said washer bearing against the outer face of a stem of a T-plate. A washer 45 is mounted on the reduced portion 42 of each feed screw and bears against the inner face of a stem of a T-plate. Jamb or locking nuts 46, 47 are mounted on threaded portions of the reduced 100 portions 42 of the feed screws and serve to fix the relation of the washers 44, 45 to the stems of the T-plates and thereby swivel the 105 110

feed screws in said plates; the relation of the screws and washers to the plates being loose in order that the stems of said plates may rise and fall in respect of the screws. A set 5 collar 48 is mounted on each feed screw 40, 41 outside of the bearings therefor, whereby to limit and determine inward movement of the screws relative to the bearings. A cross-head or turning pin 49 is mounted in and 10 transversely of the outer end portion of each feed screw 40, 41, whereby manual force may be applied to turn the screws in either direction.

In practical use the tables 25, 26 are adjusted independently through rotation of the respective feed screws 40, 41 and the movement of rotation of the screws is transmitted through the stems of the T-plates to reciprocation of the stems and tables, there- 20 by moving the table through arcs but at the same time maintaining the level position thereof. Thus the tables are raised or lowered relative to the cutter 27 to regulate and determine the depth of cut thereof on 25 an object, such as a plank, moved across the cutter in contact with the tables. It is the function of the hinges described to permit the movement of the tables through arcs relative to the angle bars 10, 11 and at the same 30 time maintain the parallel relation thereof.

I claim as my invention—

1. A jointer table and operating means therefor adapted to be mounted on a support, comprising a base frame formed of spaced, parallel side members connected and spaced by transverse bars rigidly secured thereto; a rotary cutter mounted transversely of the central portion of said frame in bearings carried by said side members; angle plates carried by both of said side members and having links pivoted to and rising from their upper ends; tables pivotally supported between the upper ends of said links, spaced from and parallel with said side members:

and means comprising a yoke depending 45 from each of said tables, a threaded standard at either end of said frame and a feed screw passing through the threaded portion of said standard and engaging said yoke, whereby said tables may be manually moved 50 through an arc, vertically.

2. In a jointer table, the combination of a base frame adapted to be secured to a support, a cutter head mounted for rotation transversely of the central portion of said frame, spaced, opposed angle plates carried by said frame at either side of said cutter head, links pivotally secured to and rising from said angle plates, tables pivotally supported between the upper ends of said links, said tables being formed of spaced, parallel side members overlain and connected by a top plate, together with manually-operable feeding means connecting said tables with either end of said frame 60 whereby said tables may be caused to move, separately, through a vertical arc.

3. In a jointer table having a base frame adapted to be secured to a support, a cutter head mounted for rotation transversely of the central portion of said frame and link supported tables at either side of said cutter head, above, parallel with and vertically adjustable relative to said frame, the combination of an independent feeding mechanism for controlling the adjustment of each of said tables comprising an open-ended yoke depending from each of said tables, a standard carried by either end of said frame beneath the outer end of each table, a manually-operable feed screw in threaded engagement with each of said standards parallel with and longitudinal of said frame and means on the inner end of each feed screw for sliding engagement with the arms of 85 said yoke.

JOHN WHISLER.
